ANTISLIPPING FOOTGEAR

Anthony De Nitzio, Plainfield, N. J.

Application March 19, 1952, Serial No. 277,463

6 Claims. (Cl. 36—59)

1

This invention relates to footgear and is more particularly directed to an overshoe designed specially for use during inclement weather conditions. The device of the invention may be worn over the conventional shoe or directly on the foot of the wearer and is provided with an outer face of anti-slipping characteristics for contact with the sidewalk or other surfaces to be traversed. The overshoe of this invention is constructed to counteract the tendency to slip and slide at various angles and positions by the provision of traction-contacting parts which materially increase the degree of purchase attainable in walking on slippery surfaces and reduce the danger of injury to body and limb encountered during periods of unfavorable weather conditions.

These and other advantageous objects, which will appear from the drawings and from the description hereinafter, are accomplished by the structure of my invention, of which a practical embodiment is illustrated in the drawings. It will be apparent, from a consideration of said drawings and the following description, that the invention may be embodied in other forms suggested thereby, and such other forms as come within the scope of the appended claims are to be considered within the scope and purview of the instant invention.

In the drawings:

Fig. 1 is a bottom plan view of an ice overshoe embodying the invention, shown partly fragmentarily,

Fig. 2 is a fragmentary perspective view of the toe portion thereof,

Fig. 3 is an enlarged fragmentary sectional view, taken on line 3—3 of Fig. 1,

Fig. 4 is a perspective view of one form of metal plate which may be used in carrying out my invention,

Fig. 5 is an enlarged fragmentary sectional view, taken on line 5—5 of Fig. 1,

Fig. 6 is a perspective view of another form of plate member which may be used in carrying out my invention, and

Fig. 7 is a perspective view of a further form thereof.

As shown in the drawings, the device of my invention comprises a footgear having a flexible upper body portion 10 of any desired or convenient outline, with any desired or convenient means to engage the wearer's foot or shoe, and a sole portion 11 secured thereto and defining therewith the general outline of the foot. The portion 11 has connected ball and heel sections 12, 13, and is formed of a relatively thick layer 14

of rubber or other flexible material, on the outer face 15 of which rows of pointed flexible teeth 16, 16' project. Said teeth are arranged in contiguous groups 17, 18, 19, of parallel rows of teeth, the groups being arranged in non-parallel relation to each other to thereby present rows of teeth arranged in parallel rows disposed at various angles to the longitudinal axis of the overshoe 9, to counteract any tendency to slide at angles to said axis.

Metallic plates 20, 20', 20'', are positioned in said sole portion 11 of the overshoe 9 at random points and in random directions to thus provide alternate rigid metallic plates and rows of flexible teeth, to further counteract any tendency to slide. The teeth 16, 16' are, as shown in Fig. 5, of uneven height to enhance the contact effect thereof and to provide constant gripping surfaces as they are worn down in use.

The metallic plates such as 20, 20', are preferably of generally planar outline so as to generally conform to the plane of the layer of rubber 14 and are provided with means such as the end portions 21 (Fig. 4) adapted to be positioned through the rubber layer 14 and clinched thereover or passed through the supplementary layers of material, such as 22, 23, which might be leather or the like, and which might be secured to the layer of rubber 14 in the fabrication of the overshoe of the present invention.

As shown in Fig. 6, the plate therein numbered 20'' may be provided with apertures 24 through which screws or the like may be passed to secure the plate 20'' to the layer 14 and/or to the layers 22, 23, or, if desired, the plate 20'' may be provided with a projection such as 25 to be passed through the layer 14 and upset thereover or otherwise secured thereto. The exposed surfaces of the plates are preferably serrated, as indicated generally at 26 in Fig. 4. Such upper surface may be made of sinuous outline, as shown in Fig. 5, to further enhance the gripping effect.

The metallic plates 20, 20', 20'', are preferably secured to the layer of rubber 14 in generally parallel planar relation thereto but preferably inwardly of the apices of said rows of teeth so that the plates will be exposed only upon depressing the shoe sufficiently to compress the layer of rubber 14 or flex the same for exposure of said plates. Or, if desired, the plates 20, 20', 20'', may be secured to the layer 14 to locate their exposed faces approximately in line with the apices of the teeth 16, 16'.

Marginal plates, as indicated at 30, 30', 30'', may be secured to the layer 14, said plates being

preferably longitudinally curved to conform to the marginal outline of the layer 14, and being of L-shaped transverse cross-section so as to define portions overlying the layer 14 and portions disposed upwardly along the margins of the overshoe of the present invention. The marginal plates are preferably serrated at their outer surfaces as shown so as to provide for increased purchase along the marginal side and bottom edges of the overshoe, as above described. The overshoe 9 of this invention provides at the ball portion 12 thereof the continuous flexible surface defined by the teeth 16, 16' arranged in parallel rows, so as to provide a relatively smooth contact with the surface being traversed; at the same time the marginal plates and the metallic plates 20, 20', 20'', provide a rougher gripping surface when required, as, for example, in traversing ice or snow or other slippery surfaces. The user need simply bear down more heavily upon the overshoe or flex the same slightly to bring into play the various metallic plates. If desired, said metallic plates might, instead of the arrangement shown in Fig. 5, be disposed so that the outer faces thereof will be parallel with those of the teeth 16, 16', or, if desired, might project slightly therebeyond. However, the form shown in Fig. 5 is believed to be a desirable form and might be used to carry out the invention. Some or all of the plates may be transversely sinuous as shown at 31, 32 of plate 26' of Fig. 7, instead of vertically sinuous as in Fig. 4, if desired.

Having thus described my invention, what I claim as new and desire to secure by Letters Patent is:

1. An anti-slipping overshoe comprising a flexible upper body portion and a generally flat sole portion secured thereto and defining therewith the general contour of a foot, adapted to be positioned on a foot or shoe to provide purchase for walking on slippery surfaces, said sole portion having connected ball and heel sections, formed of relatively thick layer of flexible material, said layer having an outer face, rows of pointed flexible teeth on and projecting from said face, said rows of flexible teeth being arranged in contiguous groups of parallel rows, which groups are disposed in non-parallel relation to each other to

present parallel rows of teeth disposed at various angles to the longitudinal axis of the overshoe, to counteract any tendency to slide at angles to said axis, and metallic plates positioned in said sole at random points and in random directions to thus provide alternate rigid metallic plates and rows of flexible teeth, to counteract any tendency to slide.

2. In an overshoe as set forth in claim 1, each of said rows of pointed flexible teeth comprising teeth of uneven height to enhance the contact effect thereof and to provide constant gripping surfaces as they are worn down in use.

3. In an overshoe as set forth in claim 1, said metallic plates being secured to said layer of rubber in generally parallel planar relation thereto but inwardly of the apices of said rows of teeth, so that the metallic plates will be exposed only upon depressing the shoe sufficiently to compress the layer of rubber or to flex the same for exposure of said plates.

4. In an overshoe as set forth in claim 1, said metallic plates having outer faces serrated and of uneven contour to enhance their gripping effect.

5. In an overshoe as set forth in claim 1, metallic plates marginally secured to said overshoe and having portions extending along the margin thereof.

6. In an overshoe as set forth in claim 1, said metallic plates having sinuous, serrated portions.

ANTHONY DE NITZIO.
